US0D1036927S

(12) **United States Design Patent** (10) **Patent No.:** **US D1,036,927 S**
(45) **Date of Patent:** **** Jul. 30, 2024**

(54) **LUNCH BOX**

(71) Applicant: **ReCup GmbH**, Munich (DE)

(72) Inventors: **Ferdinand Schütze**, Munich (DE);
Fabian Eckert, Munich (DE); **Florian Pachaly**, Munich (DE); **Hartmut Seltmann**, Munich (DE)

(**) Term: **15 Years**

(21) Appl. No.: **35/516,887**

(22) Filed: **Mar. 30, 2023**

(80) **Hague Agreement Data**

Int. Filing Date: **Mar. 30, 2023**

Int. Reg. No.: **DM/228016**

Int. Reg. Date: **Mar. 30, 2023**

Int. Reg. Pub. Date: **Apr. 14, 2023**

(30) **Foreign Application Priority Data**

Oct. 18, 2022 (EM) 015000742-0001
Oct. 18, 2022 (EM) 015000742-0002
